US00D749730S

(12) **United States Design Patent**
Dietz et al.

(10) **Patent No.:** **US D749,730 S**
(45) **Date of Patent:** **** Feb. 16, 2016**

(54) **BLADE FOR ULTRASONIC SURGICAL INSTRUMENT**

(71) Applicant: **Ethicon Endo-Surgery, Inc.**, Cincinnati, OH (US)

(72) Inventors: **Timothy G. Dietz**, Wayne, PA (US); **Stephen J. Balek**, Springboro, OH (US); **David A. Witt**, Maineville, OH (US); **Ashvani K. Madan**, Mason, OH (US); **Benjamin M. Boyd**, Fairborn, OH (US)

(73) Assignee: **Ethicon Endo-Surgery, LLC**, Guaynabo, PR (US)

(**) Term: **14 Years**

(21) Appl. No.: **29/492,794**

(22) Filed: **Jun. 3, 2014**

(57) **CLAIM**

The ornamental design for a blade for ultrasonic surgical instrument, as shown and described.

DESCRIPTION

FIG. 1 is a top perspective view of a blade for ultrasonic surgical instrument, showing my/our new design; FIG. 2 is a bottom perspective view thereof;

FIG. 3 is a top plan view thereof;

FIG. 4 is a bottom plan view thereof;

FIG. 5 is a left elevational view thereof;

FIG. 6 is a right elevational view thereof;

FIG. 7 is a rear elevational view thereof;

FIG. 8 is a front elevational view thereof;

FIG. 9 is a cross-sectional view thereof, taken along line 9-9 of FIG. 3;

FIG. 10 is a cross-sectional view thereof, taken along line 10-10 of FIG. 3;

FIG. 11 is a cross-sectional view thereof, taken along line 11-11 of FIG. 3; and,

FIG. 12 is a cross-sectional view thereof, taken along line 12-12 of FIG. 3.

The lateral recess and proximal end portion shown in broken lines is/are unclaimed environment, and form no part of the claimed design.

1 Claim, 12 Drawing Sheets
